UNITED STATES PATENT OFFICE.

WILLIAM LEE, OF GRIFFITH, TENNESSEE.

RAILROAD-TRACK CONSTRUCTION.

No. 853,308.

Specification of Letters Patent.

Patented May 14, 1907.

Application filed February 25, 1907. Serial No. 359,118.

To all whom it may concern:

Be it known that I, WILLIAM LEE, a citizen of the United States, residing at Griffith, in the county of Scott and State of Tennessee, have invented a new and useful Railroad-Track Construction, of which the following is a specification.

This invention relates to the construction of permanent ways, and has for its principal object to provide improved means for supporting and fastening the rails, with a view of eliminating all wooden ties, sills, or other supports, and for the purpose of preventing accidents through spreading or breaking of the rails.

A further object of the invention is to provide a structure in which continuous metallic sills and continuous reinforcing plates are employed to support and retain the rail in place, the rail being bolted or riveted in place at a number of points throughout its length, so that in case of breakage the parts of the rail will be retained in position and derailment prevented.

A still further object of the invention is to provide a structure in which portions of the rail supports are of such construction as to form guards to prevent shearing or breaking of the bolts or nuts in case a train is derailed.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of construction may be made without departing from the spirit or sacrificing any of the advantages of the invention.

In the accompanying drawings:—Figure 1 is a sectional perspective view of a portion of a permanent way constructed in accordance with the invention. Fig. 2 is a detail sectional view through one of the rails and sills on an enlarged scale.

Similar numerals of reference are employed to indicate corresponding parts throughout the several figures of the drawings.

In carrying out the invention, the cross ties 10 may be placed at much greater distances from each other than usual, which ties are formed of channel bars, the side webs or flanges being turned downward, so that the edges may partly embed themselves in the

ballast or other support and prevent creeping. On the ties are laid sill plates formed of iron or steel and of a length equal to that of the rails 12, thirty feet in the present instance, and the sill plates are so arranged as to break joint with the rails, the meeting ends of adjacent rails being about mid-way the length of one of the plates, and vice versa. The steel plates are secured to the ties by bolts or rivets 13, bolts being preferably employed in the preliminary assembling of the parts, and these being afterward removed for the insertion of rivets. Where the road is curved, the sill plates are shaped at the mill or factory, and the rails may afterward be laid in place and sprung around to the desired curvature and secured in position.

To secure the rails and sill plates together, angle bars 15 are employed, these bars being somewhat shorter in length than the rails and the sill plates, being generally twenty-nine feet in length, and their spaced ends being located adjacent to the meeting ends of a pair of sill plates, leaving a space of approximately two feet for the reception of angle bars 16, which are bolted to the sides of the rail, and thence pass over and partly around the meeting ends of the sill plates.

The angle bars 15 are riveted permanently to the sill plates, and their vertical webs are secured to the vertical webs of the rails by means of bolts 17 which, also, pass through inside reinforcing plates fitting against the inner faces of the vertical webs of the rails. The securing bolts 17 are arranged at frequent intervals, there being about twenty of such bolts to each rail length, so that in case of breakage of a rail no part will become detached, and derailment from this cause is avoided.

The angle bars 15 and the connecting bars 16 have the upper edges of their vertical webs turned outward forming guard flanges 20 that extend over all of the nuts by which the rails are secured in place, these guard flanges serving to prevent the shearing of the bolts by the wheels of a car in case of derailment.

The structure is especially advantageous for use in bridge work, inasmuch as the rails will be very firmly held in place, and as all wood is eliminated the structure will be rendered fire proof.

I claim:—

1. In a railroad track construction, a plurality of cross ties, metallic sill plates secured to said ties, traffic rails resting on the sill

- plates, and angle bars extending the full length of the rails and secured at intervals to both the rails and the sill plates.
2. In railroad track construction, a plurality of cross ties, sill plates secured to the cross ties and extending the full length of the road, traffic rails mounted on the sill plates and arranged to break joint therewith, angle bars extending the full length of the rails and having their vertical webs bolted thereto at intervals, the horizontal flanges of the angle bars being permanently secured to the sill plates.
3. In railroad track construction, metallic cross ties, sill plates secured thereto, traffic rails resting on the sill plates, angle bars arranged outside the rails and having their vertical flanges secured to the vertical webs of the rails, the lower horizontal flanges of the angle bars being riveted to the sill plates, and auxiliary angle bars arranged at the meeting ends of the sill plates, said angle bars being arranged to embrace portions of the sill plates, and being permanently secured to the rails.
4. In railroad track construction, cross ties, sill plates mounted thereon, traffic rails resting on the sill plates, and angle bars serving to secure the rails to the sill plates, the upper edges of the angle bars being turned outward to form guard flanges.

In testimony that I claim the foregoing as my own, I have hereto affixed my signature in the presence of two witnesses.

WILLIAM LEE.
